US00D517576S

(12) **United States Design Patent** (10) Patent No.: **US D517,576 S**
Conway et al. (45) Date of Patent: **** Mar. 21, 2006**

(54) **KNURLED ELECTRODE FOR A PLASMA ARC TORCH**

D505,963 S * 6/2005 Conway et al. D15/139

(75) Inventors: **Christopher J. Conway**, Wilmot, NH (US); **Kevin J. Kinerson**, Corinth, VT (US); **Mark Gugliotta**, Concord, NH (US); **Darrin H. MacKenzie**, Windsor, VT (US)

* cited by examiner

(73) Assignee: **Thermal Dynamics Corporation**, West Lebanon, NH (US)

Primary Examiner—Antoine D. Davis

(**) Term: **14 Years**

Assistant Examiner—Patricia Palasik

(21) Appl. No.: **29/197,680**

(74) Attorney, Agent, or Firm—Harness, Dickey & Pierce, P.L.C.

(22) Filed: **Jan. 16, 2004**

(57) **CLAIM**

(51) LOC (8) Cl. **15-09**

The ornamental design for a knurled electrode for a plasma arc torch, as shown and described.

(52) U.S. Cl. **D15/144**

DESCRIPTION

(58) **Field of Classification Search** D15/139, D15/144–144.2; 219/121.44–121.5; 313/231.31
See application file for complete search history.

FIG. 1 is a perspective view of the knurled electrode for a plasma arc torch;

(56) **References Cited**

FIG. 2 is a perspective view from the distal end thereof;
